UNITED STATES PATENT OFFICE.

GEORGE H. BACKMIRE, OF PHILADELPHIA, PENNSYLVANIA.

VAPOR-ABSORBER, SMOKE AND SOOT PREVENTER, AND HEAT-RETAINER.

1,076,942.

Specification of Letters Patent.

Patented Oct. 28, 1913.

Application filed February 26, 1912. Serial No. 680,047.

To all whom it may concern:

Be it known that I, GEORGE H. BACKMIRE, a citizen of the United States, residing at Philadelphia, in the county of Philadelphia and State of Pennsylvania, have invented new and useful Improvements in Vapor-Ab-sorbers, Smoke and Soot Preventers, and Heat-Retainers, of which the following is a specification.

10 My invention relates to new and useful improvements in a vapor absorber, smoke and soot preventer, and heat retainer for gas stoves, and has for its object to provide an exceedingly simple and effective device of 15 this character which will be light in weight, strong and durable and relatively inexpensive in the cost of manufacture.

A further object of the invention is to provide a device of this character which 20 may be placed over the flue opening of a gas stove, although it may be used with any stove burning a liquid or gaseous fuel to prevent smoke and soot leaving the stove which ordinarily soils the walls of the room 25 in which the stove is located. It also prevents the vapor, thrown off from the burning fuel and the cooking from entering the atmosphere and thus keeps down obnoxious odors, and prevents the undue escape of heat so that the oven becomes more 30 quickly heated, and the temperature is raised to a higher degree than the oven of a stove not using such a device, so that the cooking may be accomplished in a shorter length of 35 time or with a less consumption of fuel.

With these ends in view this invention consists in the details of construction and combination of elements hereinafter set forth and then specifically designated by 40 the claims.

In order that those skilled in the art to which this invention appertains may understand how to make and use the same, I will describe its construction in detail referring 45 by numeral to the accompanying drawing forming a part of this application, in which—

Figure 1, is a side elevation of my improvement showing its relation to a stove. 50 Fig. 2, a longitudinal sectional view thereof, and Fig. 3, a plan view, the cap member being removed.

In carrying out my invention as here embodied, 2 represents the extension flue or upright portion which is in the form of a conical stove pipe open at both ends, the lower

end being shaped to fit over the flange 3 of the flue opening of the stove 4.

To the outside of the extension flue 2, in proximity to its upper end is secured the flange 5 of any desired shape and size so that the upper ends of said flange and the extension flue 2 diverge to form a sand chamber 6. To the upper end of the extension flue 2 within the same is secured a suitable bracket 7 which projects upward from the extension flue approximately in line with its longitudinal axis and this bracket is provided with a head 8, about the same shape and size as the inner upper end of the cap member 9, so that said cap member will be held in one position. This cap member is closed at its upper end, but open at its lower end and this open end is of greater diameter than the upper end of the extension flue 2, so that a passage way 10 is formed between said cap member and the extension flue 2. The lower edge of the cap member 9 lies in a plane below the plane of the upper edge of the extension flue 2, or in other words their side walls over-lap.

In the sand chamber 6, is placed a suitable filtering element such as sand 11 and this is on a level with the lower edge of the cap member 9, or slightly above said lower edge in order that any vapor, grease or smoke will not escape from the cap member 9. The bracket 7 also carries a suitable absorbent material such as raw cotton 12, it being understood that said absorbent material is covered by the cap member when the device is in use.

In practice, the device is placed upon the flue opening 3, of the stove 4, and as the vaporized grease and other vapors from the burning fuel or cooking pass upward with the draft through the body 2, it enters the cap member 9, which is farthest removed from the heat and therefore the coolest. I prefer that this cap member be made of some material which will quickly condense the vapors coming in contact with the walls thereof. When said vapors reach this cap member they will be condensed and the odor therefrom will be absorbed by the absorbent material 12, while the grease which condenses on the inner walls of the cap member 9, flows downward into the sand or other filtering material 11 where it will remain, while the air escapes through the filtering material 11.

The parts of my device are so related to

one another that they virtually form a closure for the stove flue and prevent the undue escape of heat so that the temperature of the oven is quickly raised and it is found in 5 practice that said temperature reaches a higher degree than the temperature of the oven of the ordinary gas stove.

Of course I do not wish to be limited to the exact details of construction as here 10 shown as these may be varied within the limits of the appended claims without departing from the spirit of my invention.

Having thus fully described my invention, what I claim as new and useful is,—

15 1. In a device of the character described, an extension flue, means carried by said extension flue for holding a filtering material, a cap member over-lying the extension flue, the side walls thereof being spaced from the 20 side walls of the extension flue to form a passage way to the filtering material, a bracket secured to the extension flue and projecting upwardly therefrom for supporting the cap member, and an absorbent material carried by said bracket and inclosed 25 by the cap member.

2. In a device of the character described, an extension flue open at both ends, the lower end adapted to fit over the flange of a stove flue, a flange secured to said extension 30 flue in proximity to its upper end, said flange projecting upwardly and diverging from the side walls of the upper end of the extension flue producing a sand chamber adapted to hold a filtering material, a support carried by the upper end of the extension flue projecting therefrom adapted to hold an absorbent material and a cap member closed at its upper end, the lower end being of greater 35 diameter than the upper end of the extension flue, said lower end of the extension flue member over-lapping the upper end of the extension flue thereby forming a passage way from the extension flue to the filtering 40 material.

In testimony whereof, I have hereunto affixed my signature in the presence of two subscribing witnesses.

GEORGE H. BACKMIRE.
